UNITED STATES PATENT OFFICE.

SQUIRE J. JOHNSON AND GEORGE WOOD, OF SEATTLE, WASHINGTON; SAID WOOD
ASSIGNOR TO SAID JOHNSON.

BOX-SHOOK-BUNDLING MACHINE.

1,370,969.

Specification of Letters Patent.

Patented Mar. 8, 1921.

Application filed July 6, 1920. Serial No. 394,318.

To all whom it may concern:

Be it known that we, SQUIRE J. JOHNSON and GEORGE WOOD, citizens of the United States of America, and residents of the city 5 of Seattle, in the county of King and State of Washington, have invented certain new and useful Improvements in Box-Shook-Bundling Machines, of which the following is a specification.

10 Our invention relates to improvements in bundling machines and particularly in machines which are employed for bundling box shooks and similar articles as they come from the forming machine.

15 An object of our invention is to provide a machine of the kind described which will be more efficient than machines now in use for bundling and tying shooks and similar articles, and which will permit the operators to

20 work at highest efficiency in doing this work.

Another object of our invention is to provide a machine of the kind described which will be reliable and convenient in operation.

Our invention comprises those parts and 25 combinations thereof which are shown in the accompanying drawings, described in the specification, and particularly defined in the claims terminating the same.

In the accompanying drawings we have 30 shown our invention in a form which is now preferred by us.

Figure 1 is a perspective with parts broken away, illustrating our machine in 35 operation, and looking at it from the loading side.

Fig. 2 is an axial section through the lower portion of our machine.

Fig. 3 is a section on line 3—3 of Fig. 2.

In bundling box shooks there are ordinarily 40 three operations which must be performed upon each bundle, after the preliminary operation of piling the shooks. The bundle, after it is formed, must have a wire placed about each end of it and a wire must 45 then be placed across the two preceding wires and lengthwise around the bundle. These operations should be performed while the bundle is held in a clamp and before it is removed from the machine upon which it 50 is piled as it comes from the shook forming machine. Moreover, each operation, piling, and the three tying operations, consume practically an equal amount of time for each.

In order to save time and to promote the highest efficiency, we provide a bundling machine formed of four piling heads or bundle supports, which is rotatable about a central axis so that each operation may be performed progressively by different operators. Thus each step is in progress at the same time upon different bundles.

The bundles are piled upon lateral supporting arms 1. These project radially from the central pivot post 2 and should preferably be equally spaced thereabout. Each lateral supporting arm 1 may be composed of two beams, if desired, which are slightly spaced. The space between them we prefer to bridge by the plate 10. The supporting arms 1 are preferably slightly slanted to incline the bundle toward the central axis of the machine.

Upright supports 3 are connected to each of the lateral arms 1 and extend upward until they are joined, as by a spider 31, at their upper ends, where they have a pivotal support in the upper end of the pivot post 2. These uprights are preferably formed of two spaced beams, between which are placed the operating parts to be hereinafter described.

The lateral supports 1 are all secured upon a flange 21 of a sleeve 20 which is rotatable upon the pivot post 2. At its lower end the pivot post 2 may be secured in a floor flange 22. Near the lower end of the sleeve 20 we provide a series of pivot pins 23 for a purpose to be later described.

Associated with and movable upon the upright supports 3 are the bundle clamping arms 4. These are guided upon the uprights 3 by fingers 40, as shown in Fig. 1. A treadle bar 5 is pivoted at its inner end upon one of the pins 23 which are formed in the sleeve 20. The clamping bar 4 and the treadle 5 are connected by a suitable link 41, positioned between the two upright beams. We prefer to form the link with a series of holes 42 therein, these holes being adapted to fit upon a pin 43 formed in the clamping bar 4, thus permitting relative adjustment between the link 41 and the clamping bar 4. A similar connection may be made between the treadle 5 and the link 41. A spring 6, positioned between the upright beams of the support 3, and connected at one end to the treadle, at 56, and at its

other end to the upright 3, at 36, is continually under tension and serves to support the treadle 5 and the clamping bar 4 normally in raised position. We provide a 5 downwardly facing ratchet bar 51 secured upon the outer end of the lateral support 1 and engageable by the treadle 5 to secure the treadle and the clamping bar 4 in clamping position. Any other suitable securing 10 means may be employed.

The connection of the spring to the treadle at 56 may serve also as the connection for the lower end of the link 41 and the treadle. Either or both of these connections should be such that the link and the 15 spring lie inside of the outwardly-facing surface of the upright support 3. This causes the point 56 to be located near the sleeve 20, and to provide a longer leverage 20 treadle bar 5 we prefer that its inner end be offset as shown at 50 and pivoted to the pin 23 at the side of the sleeve. It is very 25 desirable that the treadle project radially from the sleeve, as the link 41 and the spring 6 are positioned between two spaced uprights 3 of each pair.

As the plate 10 bridges the space between the two lateral arms 1 of each pair, there is no chance for the end of a bundle or the 30 end of the lower shank of the bundle being pressed downwardly into this space by the pressure of the clamp. This might occur if the plate were not so placed, and a bundle of shanks were being tied. The 35 presence of the plate 10 also prevents an unskilled operator from attempting to tie a wire about the central portion of the bundle of shanks between the two spaced lateral beams. We prefer to cut away a small portion 40 of the plate 10, as shown at 11, to permit the operator to glance through the gap in using the treadle to clamp or to release. This permits the operator to glance down without moving back from the machine and 45 in this manner saves time and effort.

A method of using the machine may be as follows. Shanks sufficient to make a bundle are piled upon one set of arms 1 and uprights 3. When a bundle is completely assembled it is clamped in place and the machine rotated to bring the next set of arms in position. At the first tying station, another operator places a wire about one end of the bundle. At the next station another 50 operator places a wire about the other end of the bundle before shifting it and then, if it is desired to use a cross wire, the bundle is given a quarter turn and the fourth operator places the cross wire in place. The 55 method of use is, however, determined by the character and number of wires required. The last operator would release the bundle and remove it from the machine and this head would then be free for piling the next 60 bundle thereupon.

It will be noted that each bundle clamp is a unit independent from all of the other units in the machine. A bundle may be tied, released, shifted, or removed entirely from the machine without disturbing the remainder of the bundles. 70

With such a machine the various operations of piling, and tying, may be continued progressively and without interruption. Each operation will consume the same 75 amount of time and there is no time lost by one operator waiting for the next man to complete his operation. For special purposes there might be more than four operations required upon a single bundle and if 80 this were the case, an extra head might be provided for each extra operation. We prefer, however, to form our machine with four independent heads, as this would make it suitable for all ordinary operations. At the 85 same time less than four heads may be used if no more are required.

What we claim as our invention is:

1. A bundling machine comprising, in combination a central vertical pivot post, a plurality of spaced lateral supporting arms radially projecting therefrom and rotatable thereon, upright supports secured to each of said lateral arms, independent means associated and rotatable with each of said lateral arms for clamping a bundle thereupon, and treadle-operated means for securing each of said clamping means in clamped position. 90

2. A bundling machine comprising, in combination, a vertical central pivot post, a sleeve rotatable upon said central pivot post, a plurality of lateral supporting arms secured upon said sleeve, upright supports secured to each of said lateral arms, and independent means for clamping a bundle upon each of said lateral arms consisting of a clamping bar movable and guided upon said upright support, a pivoted treadle bar, a link connecting said treadle and clamping bars, a spring normally holding said bars in raised position, and means for securing said bars in clamped position. 100

3. In a bundling machine including a central vertical pivot post, a sleeve rotatable upon said pivot post, a bundle clamp secured upon said sleeve and comprising a lateral supporting arm, an upright support secured thereto, a bundle clamping arm movable and guided upon said upright support, a treadle bar projecting radially from said sleeve and offset at its inner end, and pivoted upon the side of said sleeve, a link secured to said treadle near the sleeve and connected to said clamping arm, a spring normally holding said treadle and clamping bar in raised position, and means for securing said bar in clamped position. 115

4. In a bundling machine including a central vertical pivot post, a sleeve rotatable 120

upon said pivot post, a bundle clamp secured upon said sleeve and comprising a lateral supporting arm, an upright support secured thereto, a bundle clamping arm movable and guided upon said upright support, a treadle bar projecting radially from said sleeve and offset at its inner end, and pivoted upon the side of said sleeve, a link secured to said treadle near the sleeve and connected 5 to said clamping arm, said link having a series of holes therein and said clamping bar having a pin adapted to be received in said holes to permit relative adjustment of these parts, a spring normally holding said 10 treadle and clamping bar raised, and means for securing said bar in clamped position.

5. A bundling machine comprising, in combination, a lateral supporting arm, an upright support secured thereto and formed 15 of two spaced members, a clamping bar mounted to slide upon said upright members and extending over said lateral arm, a treadle pivoted beneath said lateral arm and extending therebeneath, a link extend-

20

25

and means for holding said clamping bar in 30 clamped position.

6. A bundling machine comprising, in combination, a lateral supporting arm, an upright support secured thereto and formed 35 of two spaced members, a clamping bar 35 mounted to slide upon said upright members and extending over said lateral arm, a treadle pivoted beneath said lateral arm and extending therebeneath, a link extending 40 between said spaced upright members and connected to said clamping bar and said treadle, a spring lying between said spaced upright members and secured at one end thereto and at its other end to the treadle, and means for holding said clamping bar 45 in clamped position, and means for adjusting the effective length of said link to adjust the device for different thicknesses of bundles.
